UNITED STATES PATENT OFFICE.

BENJAMIN ANDREWS, OF HOUSTON, TEXAS, AND WILLARD C. AVERILL, JR., OF MERAUX, LOUISIANA.

APPARATUS FOR TREATING HYDROCARBONS.

1,312,467.

Specification of Letters Patent. Patented Aug. 5, 1919.

Application filed February 10, 1917. Serial No. 147,780.

To all whom it may concern:

Be it known that we, BENJAMIN ANDREWS, residing at Houston, in the county of Harris and State of Texas, and WILLARD C. AVERILL, Jr., residing at Meraux, in the parish of St. Bernard and State of Louisiana, both citizens of the United States, have invented or discovered certain new and useful Improvements in Apparatus for Treating Hydrocarbons, of which the following is a full, clear, and complete disclosure.

Our invention relates to apparatus for treating comparatively heavy petroleum and other hydrocarbon oils and their distillates and derivatives, in order to produce from such heavy oils a large yield of gasoline or other light, easily volatile liquids.

One object of our invention is to provide apparatus of the kind described, which will be safe and efficient, and by the use of which large yields of gasoline and light hydrocarbon liquids may be obtained from heavy oils, and which will be free from trouble arising from the accumulation of carbon.

Other objects and advantages of our invention will be obvious from the following specification.

In practising our invention, we cause heavy hydrocarbon oil, or the vapors thereof, to be heated and converted into lighter liquids by passing it through tubes containing a heated liquid of such a character that it will not distil or vaporize at the temperature required for converting the oil.

The arrangement employed is such that the liquid in the tubes is mixed with the oil vapors, and is rapidly circulated through the tubes. When operating in this way, we find that the tubes may be comparatively short; that large quantities of oil may be passed through them, and that large yields of gasoline may be obtained from heavy oils that would yield practically no gasoline if subjected to a straight distillation process; moreover, we find that the presence of the liquid in the tubes, particularly when kept in rapid circulation, effectively prevents the accumulation of carbon, so that after extensive runs the tubes remain practically clean.

Our process may be carried out at atmospheric pressure, but we prefer to maintain the heated liquid in the tubes under a uniform pressure, higher than atmospheric pressure. This super-atmospheric pressure may be obtained by restricting and regulat-

ing the escape of the hydrocarbon vapors; but preferably, and more conveniently, by subjecting the apparatus, including the liquid in the tubes, to the pressure of steam admitted and maintained at a uniform pressure. The vapors on leaving the tubes may be condensed and separated in any well-known way; but we prefer to conduct them first to a dephlegmator or separating tank, where the heavy oils may be condensed and separated out, and then to a condenser maintained at a comparatively low temperature but also preferably maintained under pressure, in which condenser the light oils are condensed and drawn off.

In the drawing accompanying and forming a part of this specification, we have illustrated apparatus embodying and adapted for use in practising our invention, which will be readily understood from a description of this apparatus and its mode of operation.

In the drawing: Figure 1 is a vertical section of the complete installation; Fig. 2 is a side elevation, partly in section, of the furnace, including the tubes containing the heated liquid and through which the hydrocarbon is to be passed; Fig. 3 is a detail section view of two of the tubes. Fig. 4 is a detail section view of the pressure regulating valve employed to maintain pressure in the still and condensers.

Referring in detail to the drawing, we have shown at 1 a furnace which may be of any conventional type. This furnace supports a header 2, to the lower side of which there are secured a plurality of U-shaped tubes 3. The ends of these U-shaped tubes open into the header 2, and the body of the tubes extends from the header down into the furnace, so as to be heated. An oil supply pipe 4 is disposed in one leg of each of the U-shaped tubes, and these pipes 4 are all connected with a common oil supply header or pipe 5, so that by opening the cocks 6 and 6^a, the oil to be treated may be caused to flow down the tubes 4 and into the heated liquid in the pipes 3. The pipes 3 are filled with a heated liquid such as melted lead, which will not distil at the temperature employed, and this heated liquid extends up into the header, with its surface at the level indicated by the broken line *a*, Fig. 1. 7 designates a dephlegmator or air-cooled condenser, and this is filled with broken

pottery or other material adapted to expose a large surface to the vapors. This dephlegmator is connected with the header 2 by the pipe 8, and also through the pipe 9 with the water-cooled condenser 10. 11 designates a tank adapted to receive the light liquids condensed in the condenser 10. Any fixed gases passing into this tank 11 may be permitted to escape through the pipe 12, and the light hydrocarbons may be drawn off through the pipe 13. When it is desired to operate the apparatus under a uniform pressure, this may conveniently be done by admitting steam into the dephlegmator 15 through the pipe 14 and valve 30, which is preferably a pressure regulating valve adapted to admit steam at the pressure desired.

In using the apparatus described, we proceed as follows:

The heavy hydrocarbon oil is supplied to the header 5 under pressure, and flows from this header down through the small pipes 4 into the melted metal in the tubes 3. This 25 metal is maintained at a temperature suitable for converting the oil, and this will vary with the character of the oil treated. When treating a distillate of 32 degrees Bé., we have found a temperature of 500 degrees 30 C. and a pressure of 75 pounds to give good results. It is to be understood, however, that both the pressure and temperature may, and should be varied, in order to get the best results. An operator, by noting the results 35 had with the particular oil treated, can readily determine the most advantageous values for temperature and pressure. We preferably provide a thermometer 35 disposed in the liquid in the header, and also 40 a thermometer 37 disposed in the vapors in the header, whereby temperature observations may be made. The melted metal in the tubes is kept in rapid circulation by the liquid, which immediately vaporizes on coming in contact with the metal and rises in the form of bubbles, as indicated in Fig. 3. This causes the lead to rise in one leg of the tube and to descend in the other, as indicated by the arrows. The vapors pass 45 through the header 2 to the dephlegmator, as above explained, and the heavy oils, along with any water of condensation accumulating in this device, may be drawn off from time to time through the outlet 17. The lighter 50 vapors pass through the dephlegmator 7 into the water-cooled condenser 10 and are condensed in tank 11, as above explained. The steam admitted through the pipe 14 and reducing valve 30, with coöperation of 55 a pressure relief and regulating valve 15, which is set so as to throttle the escaping mixture, operates to maintain a uniform pressure throughout the apparatus.

In actual operation the only appreciable

accumulation of carbon noted, is on the surface of the melted lead in the header 2, and this may be easily removed by shutting off the oil supply and opening the cock 40 and admitting live steam through cock 41 so as to blow out the carbon. 65

We have found the arrangement described above for separating and condensing the product flowing from the still, by which we mean the tubular apparatus for heating the liquid, to be particularly adapted for this 70 use. It should be understood, however, that the use of the tubular heating still is in no way limited to such condensing and separating apparatus, as other well-known arrangements may be used. 75

The method or process described herein in connection with our improved apparatus, by reason of an official requirement for division, is not claimed herein and does not form a part of this invention, but is described and claimed in our pending application Serial No. 254,737, filed September 19, 1918. 80

While we have disclosed only one arrangement of our improved apparatus, we are aware that modifications may be made therein without departing from the scope of our 85 claims. 90

What we claim is:—

1. Apparatus for treating hydrocarbon oils comprising a tubular circulatory heating system, means for maintaining a molten metal in said tubular circulatory heating system, and means for injecting oils into said molten metal and for conducting away 95 the resulting vapors. 100

2. Apparatus for treating hydrocarbon oils comprising a tubular circulatory heating system, means for maintaining a molten metal in said tubular circulatory heating 105 system, and an interior oil supply pipe disposed in said system and arranged to discharge oil into the said metal for the purpose described.

3. In apparatus of the kind described, a 110 conduit having up and down flow passages, means for heating and maintaining a refractory liquid therein of a kind that will not vaporize at the temperatures employed, means for injecting the hydrocarbon to be treated in the up flow passage of the conduit, and means for separating the resulting vapors from the liquid maintained in the tubes, substantially as described. 115

4. Apparatus for treating hydrocarbon 120 oils comprising a reservoir, a conduit opening into the said reservoir having up flow and down flow passages, means for heating and maintaining a refractory liquid in said conduit, means for injecting the hydrocarbon to be treated in the up flow side of the conduit so as to set up a circulation of the liquid therein, the liquid in said conduit be- 125

ing of a kind that will not vaporize at the temperature required for converting the hydrocarbon oil, substantially as described.

5. Apparatus for treating hydrocarbon oils, comprising a U-shaped tube, a melted metal in said tube, and an interior oil supply pipe disposed in one leg of said "U" tube and arranged to discharge oil into said melted metal, for the purpose described. 30

35

5. Apparatus for treating hydrocarbon oils, comprising a reservoir, a U-shaped pipe having its open ends secured to and opening into said reservoir, a heated liquid in said pipe, and means for injecting the substance to be treated into one leg of said U-shaped pipe, 40

10 said heated liquid being distinct from the substance to be treated.

15 6. A reservoir, a U-shaped pipe having its open ends secured to and opening into said reservoir, a melted metal in said pipe, and means for injecting the oil to be treated into 45

one leg of said U-shaped pipe.

7. A reservoir, a plurality of U-shaped tubes, each having its open ends secured to and opening into said reservoir, a melted metal in said tubes, an oil delivery pipe disposed in one leg of each of said U-shaped pipes, all for the purpose described. 50

8. A reservoir, a plurality of U-shaped

tubes, each having its open ends secured to

and opening into said reservoir, a melted

metal in said tubes, an oil delivery pipe dis-

posed in one leg of each of said U-shaped

pipes, all for the purpose described.

9. Apparatus for treating hydrocarbon

oils, comprising a receptacle containing a melted metal, means for passing the oil to be treated through the metal, and means for admitting steam into said receptacle for the purpose of blowing out any carbon accumulating on the surface of the metal, substantially as described.

35

10. Apparatus for treating hydrocarbon oils, comprising a reservoir, a tube having its two ends secured to and opening into said reservoir with its body portion in the form of a loop extending downwardly, the tube and a portion of the reservoir being filled with melted metal, means for heating the metal and maintaining it in melted condition, and means for injecting the hydrocarbon to be treated into the metal contained in the tube, all for the purpose as described. 40

11. In apparatus of the kind described a conduit having up and down flow passages or sides, means for heating and maintaining a melted metal therein, and means for injecting hydrocarbon to be treated in the up flow side of the conduit so as to set up a rapid circulation of the melted metal through the conduit. 50
